UNITED STATES PATENT OFFICE.

MARY AGNES KELLY, OF NEW YORK, N. Y.

DEVICE FOR TURNING BOTTOMS OF SKIRTS.

No. 854,294.

Specification of Letters Patent.

Patented May 21, 1907.

Application filed August 13, 1906. Serial No. 330,389.

To all whom it may concern:

Be it known that I, MARY AGNES KELLY, a citizen of the United States, residing at New York, in the county of New York and State 5 of New York, have invented a new and useful Device for Turning Bottoms of Skirts, of which the following is a specification.

One of the hardest things in dressmaking is to turn up the bottom of a skirt so that it 10 will hang the same distance from the ground all around. This has to be done with the skirt in position, as it is difficult to get accurate measurements for this purpose from the waist, owing to the way a skirt may hang 15 and to irregularities of the figure. This operation is now done by fitting a skirt in place and then going around the bottom of the same with the hands and turning up and pinning or chalking the proper line. This operation 20 is a difficult one and one that does not necessarily lead to the desired result, even if done by a skilled fitter.

The object of this invention is to provide a device by which this operation can be accurately, 25 readily and quickly performed without the need of a skilled fitter.

To this end, the invention consists of a folder, usually made in trough-shape form, arranged on a stand for gaging from the floor. 30 The folder is usually made adjustable on the stand. By setting the folder at the desired height and starting a fold in the skirt, the folder can be progressively moved around the bottom of the skirt and the fold turned 35 up all the way around the same distance from the floor, and by pinning or temporarily securing the fold as it is made, the skirt can be fitted to hang the same distance from the floor all the way around.

40 The device is shown in the accompanying drawing forming part of this specification, in which

Figure 1 is a perspective view showing the device in operation, and Fig. 2 is a perspective view on an enlarged scale showing the device.

In detail, A designates a suitable base projecting from which are two posts B—B forming a stand. Each of these posts is provided 50 with a series of notches or holes and each post is graduated for adjusting purposes.

C designates the folder. This folder is

usually made out of a piece of brass bent to the proper shape and is usually nickel plated so as to present a smooth surface. The 55 folder is cut out as at D. Secured to the top of the folder is a piece of spring wire E, which is bent to have projecting arms which may be snipped into the holes in the posts B—B.

In operation the folder is set to proper position on the posts. The device is then placed in position under a part of the skirt and the bottom of the skirt is turned up so as to form a fold in the bottom of the folder C. With the stand resting on the floor the device is then moved around the bottom of the skirt and the fold temporarily fastened. This will progressively carry the fold around the bottom of the skirt and will insure that the finished bottom of the skirt will be exactly the same distance from the floor all the way around.

The cut-away portion D in the folder forms a convenient place for pinning the fold as it is progressively made and this pinning 75 will be accurate as it is done between two rigidly held portions of the fold. Thus, by this device, the adjusting of the bottom of a woman's skirt can be accurately performed.

The device may be made in many different 80 forms and shapes for carrying out this invention without departing from the scope of my invention as expressed in the claims.

Having thus fully described my invention, what I claim and desire to secure by Letters 85 Patent of the United States is:—

1. A turner for skirt bottoms, comprising a trough-shaped folder having an aperture at the bottom thereof for receiving a pin or other fastening means to secure the fold. 90

2. A turner for skirt bottoms, comprising a trough-shaped sheet metal folder having an aperture in the bottom thereof extending through both folds, through which the fold in the skirt may be secured by a pin or the like. 95

3. A turner for skirt bottoms or the like, comprising a pair of upright posts, a folder, and resilient means for holding the folder in adjusted positions between the posts. 100

4. A turner for skirt bottoms, comprising a pair of upright posts graduated by notches on their contiguous faces, a folder, a double arm spring secured to the folder and adapted

to engage with said notches to hold the folder in adjusted positions.

5. A turner for skirt bottoms, comprising a base, posts projecting therefrom and provided with notches, and a trough-shaped folder having spring arms for engaging in said notches.

In testimony whereof I have hereunto set my hand, in the presence of two subscribing witnesses.

MARY AGNES KELLY.
